BLASTING PROCESS

Dent Ferrell, Carterville, and Arthur W.
Helmholtz, Harrisburg, Ill.

Application August 25, 1933, Serial No. 686,672

1 Claim. (Cl. 102—5)

Our invention relates to the blasting of coal or other material and contemplates improvements in existing processes and apparatus. The principal object of the invention is to increase the effectiveness of blasting processes and apparatus. The invention is applicable to those methods and apparatus wherein thermal explosives, such as powder and dynamite, are used and also to those methods and apparatus wherein the blasting medium, such as air, carbon dioxide and the like, is confined in a cartridge or other receptacle and released therefrom by rupture of the container due to the pressure of the medium therein or by mechanical, hydraulic, electrical or other means. The invention consists principally in placing the coal body or other material in a state of strain by forcing into it a fluid, gas or mud stream under sufficient pressure to set up the desired strain. The pressure building medium is applied to the body through the drill hole in which the blasting agent is placed. The initial pressure fills up all fissures, laminations and cracks in the vicinity of the drill hole and builds up a strain which greatly increases the effectiveness of the main blasting operation.

We are aware that it has heretofore been proposed to mine coal and the like by pumping water or other liquid or fluid into the coal body for the purpose of breaking it up. However, such processes cannot be effective due to the unavoidable loss of pressure in the voids and laminations in the body. Our process, therefore, contemplates merely the building up of pressure in the vicinity of the drill hole to a point where leakage through the ore body makes higher pressure impracticable such initial pressure and strain greatly increasing the effectiveness of the main blasting operation.

The invention further consists in the blasting process and apparatus, in the parts and combinations and arrangements of parts and in the sequence of operations hereinafter described.

In the accompanying drawing,

Fig. 1 is a diagrammatic sectional view through a portion of a coal body and through a blasting cartridge embodying our invention;

Fig. 2 is a similar view of a modified construction; and

Fig. 3 is a similar view showing an embodiment using a thermal explosive.

Referring to Fig. 1, a recess A is drilled into a body of coal B, in which fissures or crevices C are indicated. Mounted in the drill hole A is a blasting cartridge D and the end of the drill hole is closed by a suitable plug E. The cartridge D is provided at one end with a threaded bore 1 in which is received a threaded nut 2. Against this nut is mounted a disk 3 of comparatively weak material and a retaining nut 4 is mounted in the extreme end of the cartridge

against said disk. Extending through the plug 3 is a line 5 for supplying air or other gas or liquid under pressure, said line being connected with the end of the cartridge and a passageway 6 communicating with said supply line and with the interior of the cartridge. When the pressure in the cartridge is built up to a sufficient point, the disk is broken and the released pressure breaks up the coal body.

Our invention builds up an initial strain in the coal body to intensify the effect of the blasting operation. In the construction shown in Fig. 1, the end of the blasting cartridge D opposite the pressure inlet is provided with a valve body in which is mounted a suitable bleeder valve 1. Thus, a portion of the pressure medium entering the cartridge passes through said valve and builds up pressure and strain in the surrounding coal body. By the time the disk 3 is broken, as a part of the main blasting operation, a considerable pressure has been built up in the surrounding coal body and the effectiveness of the blasting operation is greatly increased.

In the construction shown in Fig. 2, a simple cartridge D' is used which is entirely closed except for a connection with the main pressure supply line 5a. A separate pressure line 8 with a suitable control valve 9 extends through the drill hole plug E' so that pressure may be built up in the coal body. This second pressure medium may be the same as that used for the main blasting operation, or it may be water or any other suitable fluid.

Fig. 3 shows a dynamite cartridge D'' of common design and a pressure line 8a for building up pressure in the coal body. The dynamite is discharged after suitable pressure has been built up.

The above described process and apparatus greatly increase the effectiveness of blasting operations, and are simple and comparatively inexpensive. Obviously any desired means may be employed for the main blasting operation and many means are available for building up the initial pressure. Accordingly, the foregoing description should be regarded as illustrative and we do not wish to be limited to the precise details shown.

What we claim is:

The process of blasting which comprises providing an opening in the body to be blasted, inserting a blasting cartridge into said opening, plugging the end of said opening and then forcing fluid under pressure through said opening into the surrounding body and building up pressure in said body prior to operating the blasting cartridge.

DENT FERRELL,
ARTHUR W. HELMHOLTZ.
